PRODUCTION OF AROMATIC BODIES

Charles Weizmann, London W. C. 1, England

Application January 9, 1942, Serial No. 426,243
In Great Britain April 23, 1941

2 Claims. (Cl. 260—668)

This invention relates to aromatic bodies, namely, the production of aromatic hydrocarbons.

I have found that mineral oils, especially of relatively high-boiling range, are converted into aromatic hydrocarbons, to a considerable extent such of comparatively low-boiling point, such as benzene, toluene, xylenes and ethylbenzene. The process consists in passing the vaporised mineral oil over a metallic catalyst belonging to the group of metals catalysing hydrogenation and dehydrogenation reactions. Together with gaseous products, such as hydrogen, methane, ethane, propane, butane and the corresponding olefins, a liquid is formed, which, apart from a very small amount of low-boiling (below 80° C.) highly unsaturated material, consists of aromatic hydrocarbons. It is assumed that the hydrocarbon molecules break down to very small units, such as olefins, dienes and acetylenes. The cracking products are then di- or polymerised, cyclised, if necessary, and dehydrogenated. All these processes appear to be catalysed by the same, above-mentioned catalyst.

The process is a true cracking process, as its distinct feature is the production of substances chiefly of lower molecular size, compared with the starting material. As with other cracking processes, a certain part of the product has a boiling range higher than that of the initial material.

Further I have found that a low-boiling bituminous shale oil (50–180° C.), and a low-boiling, low-temperature coal oil (100–180° C.), may be converted into aromatic hydrocarbons. It has now been discovered according to this invention that such conversion is not limited to oils such as shale oil and coal oil but that low-boiling petroleum fractions in general, natural or synthetic, provide good starting material for the process of aromatisation.

The product substantially consists of pure and easily separable aromatic hydrocarbons, notably benzene, toluene and a product, boiling at 136–145° C., being pure ethylbenzene or a mixture thereof with small quantities of xylenes and styrene, depending on the nature of the starting material processed. With a straight-run gasoline of boiling range 100–180° C., e. g. under certain well-defined conditions, as much as 7% benzene, 14% toluene and 14% xylenes, containing ethylbenzene and styrene have been isolated, together with a minor quantity of higher alkylbenzenes, boiling between 140 and 180° C. (6%) and a heavy oil (5%), all the percentage figures being calculated on the feeding-stock. As the product obtained has a boiling range similar to that of the raw material processed, the new process may be described as "catalytic, aromatising reforming"; it must, however, be remembered that part of the material is recovered as a high-boiling mixture

of aromatic hydrocarbons, containing naphthalene, anthracene and other polycyclic compounds.

Part of the material is converted into gaseous products. The gases contain hydrogen, methane, ethane and ethylene, propane and propylene, butanes and butenes and the like and are therefore useful for further transformations, at least the unsaturated constituents, propane and the butanes. The remainder may be used as fuel or for other purposes. A further by-product, obtained in comparatively very small amount, is a very low-boiling liquid (25–80°) which contains olefines, dienes and the like and may be utilised accordingly. It is evident, therefore, that the liquid product obtained in my process, aside from a small, low-boiling, highly-unsaturated product, consists substantially of aromatics covering the entire range from benzene to polycyclic compounds.

The process may be carried out in general terms as follows:

The vaporised feeding-stock or a mixture of the vapours with inert gases passes at a temperature ranging between 600 and 750°, but preferably in the neighbourhood of 650° C. and at a pressure substantially near atmospheric pressure, over a catalyst, consisting of a metal chosen from the group given below, or a mixture or alloy of a plurality of such metals, either in compact form or deposited on a carrier, such as asbestos, pumice, bentonite and the like, which in itself has no catalytic effect on the hydrocarbon vapours under the specified conditions. The catalyst is placed in a horizontal or vertical steel tube, the material of which may or may not effect the same conversion as the catalyst, which will always have the predominant influence on the vapours, due to its much larger active surface. The catalyst metals are chosen from the group of hydrogenation and dehydrogenation catalysts, that is to say, from the group consisting of chromium, cobalt, copper, iron, manganese, molybdenum, nickel, platinum metals, for example, palladium, as well as silver, tungsten and vanadium, mixtures containing a plurality of these metals and alloys containing a plurality of these metals. The gases, leaving the catalytic chamber, are cooled efficiently, whereby most of the products liquid at room temperature are separated. A minor part of them remaining in the cracking gases is stripped by suitable solvents, such as spindle oil, and the permanent gases are collected and utilised as desired. The products dissolved in the scrubbing liquid are removed by heating and together with the first liquid product subjected to a careful fractionation. It is also possible to isolate the reaction products by a process of fractional condensation. The aromatic products, so isolated with great ease, are substantially pure

and may or may not be further purified by the usual methods.

It is not necessary to use a purified material. Even crude oils give favourable results, as the method causes desulphurisation simultaneously with the aromatisation: the sulphur, which may be present in the feeding-stock in form of organic sulphur compounds, is converted into hydrogen sulphide, and even the nitrogen of nitrogenous compounds present is recovered in form of ammonia. With increasing boiling range of the feeding-stock the process of aromatising reforming gradually approaches that of aromatising cracking described above.

The catalyst does not become appreciably inactivated by carbonisation, which occurs in similar processes known in the conversion of hydrocarbon oils. If, however, a marked decrease in activity has taken place, the reactivation can be effected by successive treatment with oxygen or oxygen containing gases and hydrogen or hydrogen containing gases at appropriate temperatures. For the second step in this re-activation, the gases may conveniently be used which remain after removal of the otherwise useful constituents from the gaseous products, obtained by the process of catalytic, aromatising reforming itself.

The ease with which the low-boiling hydrocarbon oils are aromatised, is ascribed to the co-operation of two mechanisms:

(1) That described above, involving destruction of the molecules into low-molecular unsaturated compounds, such as ethylene, propylene, butylene, butadiene, acetylene, their di- or polymerisation, cyclo-isomerisation, or dehydrogenative cyclisation of the polymerisation products, if they are not already hydroaromatic, and dehydrogenative aromatisation. It is significant that the amount of olefines in the cracking gases is lower when the speed of throughput is relatively low—indicating that these olefines are aromatised to a higher proportion—and the

(boiling range) of the feeding-stock, at least as far as the production of low-boiling aromatics is concerned.

These considerations make it clear that not all the hydrocarbons present in a gasoline are aromatised with equal ease. Substances like methyl-pentane or ethylbutane, in general with less than six carbon atoms in a straight chain, can only be aromatised by the first mechanism, and structural influences will always play a part in the speed and ease of aromatisation.

The invention consists in a process for the conversion of aliphatic and hydroaromatic mineral oil bodies as herein set out into a product comprising a liquid mixture of aromatic substances by subjecting a starting material as herein set forth to treatment by heat within the temperature range of 600-750° C. for the production of a mixture of substantially pure aromatic hydrocarbons, in contact with a hydrogenation and dehydrogenation catalyst.

The invention also consists in processes for the conversion of aliphatic and hydroaromatic mineral oil bodies as herein set out into a product comprising a liquid mixture of aromatic substances substantially free from sulphur and nitrogen compounds substantially as herein described.

I will now give particulars relating to the feeding-stock which have been employed in certain examples of the present invention. Then follow particulars of an example applied to the employment of one of the feeding-stocks mentioned, followed by another specific example and then by tabulated references to other examples more details of which are shown in graphs as indicated later.

FEEDING-STOCK FOR THE AROMATISING REFORMING

Samples of Texas Crude 27 A. P. I. light distillates and their extracts, prepared with 150% liquid sulphur dioxide, used had the following characteristics:

	Sample A (gasoline 100-180° C.)	Sample B (extract 100-180° C.)	Sample C (gasoline 150-230° C.)	Sample D (extract 150-250° C.)
Spec. gravity (60° F.)	0.700	0.797	0.839	0.855
Aniline point	48	43	50.75	23.0
I. B. P.	°C.	98	94	162
10%	111	104	170	163
20%	114	110.5	177.5	175
30%	119	117.5	183	182
40%	125	125	188	185
50%	132	132.5	192.5	193
60%	138	140	200	200
70%	146	149	207	207
80%	154	157	216	215

F. B. P.	do	186	191	250
Bromine consumption mg./g.		8	111	8
Solubility in dimethyl sulphate	percent	18	18	10

formation of low-boiling aromatics from higher-boiling gasolines can most easily be explained by the operation of this mechanism.

(2) A direct cyclo-isomerisation of olefines and dehydrogenative cyclisation of paraffins present in the feeding-stock, followed by the dehydrogenation of the products (and of hydroaromatic hydrocarbons present as such) into aromatics of substantially the same number of carbon atoms. It can well be imagined that some of the products formed due to the first mechanism by di- and polymerisation of the simple olefines, are already present in the feeding stock. This mechanism becomes obviously suppressed with the increasing molecular weight

65 Referring to the five accompanying graphs, Graphs I to IV have reference to gasoline and Graph V has reference to heptane. All the graphs show the relationship between temperature in degrees centigrade and percentage of distillate.

In Graphs I-IV the full-line curves *a* apply to gasoline or gasoline extract. The dash curves *b* apply to the cracked product and where shown, namely, in Graphs I and II, the chain curves *c* apply to further cracked products.

Ia is for the gasoline of boiling range of 100-180° C., sample A above. *IIa* is for the gasoline

extract of boiling range of 100-180° C., sample B above. IIIa is for the gasoline of boiling range of 150-250° C., sample C above, and IVa is for the gasoline extract of boiling range of 150-250° C., sample D above.

The dash curves b are all for products obtained by cracking at 650° C. The chain curves c are both for products obtained by cracking at 680° C.

In Graph V, the vertical full-line d applies to heptane and the dash-line e applies to the product cracked at 580° C.

EXAMPLE 1.—AROMATISING REFORMING OF SAMPLE A

The catalyst consisting of a mixture of fine copper and iron turnings in the ratio of 5:1 and placed in a steel tube of 1 metre useful length and 7.5 cm. diameter, was activated, by successive oxidation with air at 400° C. and reduction with hydrogen at 250° C. and was then brought to a temperature of 650° C. Into the catalytic furnace, 1 kg. of the gasoline sample A was introduced at a rate of 126 g. per hour. The vapours of the reaction product were cooled with an efficient water-jacketed condenser, giving 452.5 g. liquid product, and were then passed through a tower, filled with 450 cc. spindle oil, which absorbed 83.5 g. liquid products. These were re-

were shown to be entirely aromatic by the usual methods. The effect of the process is demonstrated by Graphs Ia and Ib, which contain the boiling curves of the initial and the final product.

5 It is possible to increase the amount of low-boiling aromatics, and of the very high-boiling aromatics, by re-cycling the fraction boiling at 145-180° C. over the same catalyst.

10 The fraction 145°-180° was subjected to fractionation and was shown to contain the following principal constituents:

	Boiling point, degrees
Isopropyl-benzene	151
1,3,5-trimethyl-benzene (mesitylene)	162
15 Tert. butyl-benzene	168
1,2,4-trimethyl-benzene	170
Sec. butyl-benzene	174
1,2,3-trimethyl-benzene	179
Indene	181

20 The mixture of these substances can be used as such as ingredient for high-grade motor-fuel in view of its fairly high octane number, but it can also be degraded by re-cycling to substantial amounts of the low boiling aromatics as described below.

25 A similar fractionation of the part of the product boiling under atmospheric pressure above 180° C. led to the following substances:

Substance	Boiling range	Percent of total high fraction	Remarks
Tetra hydronaphthalene	205°-210° C.	5.0	
Naphthalene	210°-225°	11.3	
α-Methyl-naphthalene	240°-247°	4.2	
α-Ethyl-naphthalene	252°-258°	5.0	Picrate M. P. 116°.
Unidentified	265°-275°	4.2	Picrate M. P. 122-123°.
Do.	185° in vacuo	2.1	Orange red picrate M. P. 134°.
Anthracene	240°-260° in vacuo	12.0	
Unidentified substance	345°-347° in vacuo	7.3	Dark-red picrate M. P. 196-198°.
Unidentified hydrocarbon	350°-410° in vacuo	1.0	M. P. 288°.
Pitch	Above 410° in vacuo	25	

covered by heating the scrubbing liquid to 200° C. and were combined with the first liquid.

The non-condensable gases amounted to 408 litres with a specific density of 1.149 g. per litre, i. e. to 469.2 g. A sample of gas was taken before the scrubbing tower and showed the following composition:

	Percent (by volume)	Percent (by weight)	Total amount formed from 1 kg. gasoline	Grams
Hydrogen	13.90	1.10	5.2	
Methane	37.85	23.50	110.2	
Ethane	9.70	11.30	53.0	
Ethylene	15.40	16.75	78.8	
Propane	1.85	3.15	14.8	
Propylene	10.30	16.80	78.8	
Butanes	0.45	1.00	4.7	
Butylenes (α and β)	3.55	7.70	38.4	
Iso-butylene	2.90	6.30	29.5	
Pentanes and pentenes	2.05	5.67	26.6	
Hexanes and hexenes	2.05	6.75	31.9	

The liquid reaction product was subjected to a careful fractionation, and the following cuts were secured:

	Grams
Product boiling up to 80° C.	22.7
Benzene (80-81° C.)	75.0
Toluene (110-113° C.)	152.0
Xylene fraction (135-145° C.)	152.7
Higher alkylbenzenes (145-180° C.)	68.4
Heavy aromatics (boiling above 180° C.)	58.5

Tolerance ±2%.

All the products, apart from the lowest one, 75

Substantial quantities of anthracene and especially chrysene may be isolated from the pitch.

45 The above list contains only the substances which have been isolated in substantial quantities; it does not indicate that the tabulated compounds are the only products formed.

According to a modification the charging stock was passed over a catalyst consisting of activated copper at a temperature of 600° C. The total catalyst volume was 640 cc. of which 440 cc. were at the indicated temperature, while the temperature decreased by about 15° towards the ends of the furnace. As the rate of throughput was 70

55 cc. per hour, the space velocity was 0.16 litre per litre catalyst space per hour. 96% liquid product were recovered, while 4% of the charging stock were converted into gaseous products. The composition of the liquid product was, however, different from that of the starting material: 15% boiled up to a temperature of 145° C., 10% above 195°, so that 75% had retained the original boiling range. Fractionation of this part showed that the relative amount of trimethyl-benzenes had increased; the constituents containing in their molecule longer side-chains are more sensitive under the conditions of the process. Fractionation of the product boiling below 145° showed that it consisted of the following components expressed in per cent of the total charge:

	Per cent
Below benzene	1.3
Benzene	1.5
Toluene	1.5
Ethyl-benzene fraction	12.0

Similar experiment was carried out at 680° C. The total catalyst volume was 550 cc. of which 240 cc. had the stated temperature. In order to have approximately the same space velocity (0.19) the rate of throughput was fixed at 45 cc. per hour. The total weight of the charge was recovered, of this 73% in liquid and 27% in gaseous form. Of the liquid, 48% boiled below 145° C., 18% boiled between 145°-190°, 34% boiled above 190°.

Fractionation of the low fraction showed that it consisted of

	Per cent
Head fraction	0.7
Benzene	3.5
Toluene	8.0
Ethyl-benzene	16.5

The total amount of low boiling aromatics is therefore higher than at 600° C. and the increase in toluene is especially marked. In both cases, however, the ethyl-benzene fraction is the principal constituent.

In the fraction boiling between 145°-190° C. 55% are mesitylene.

From the highest fraction naphthalene and anthracene were easily isolated; about 50% of this fraction consisted of chrysene.

OTHER EXAMPLES IN TABULAR FORM

The results of other examples are summarised in the following table, and the effect of processing is demonstrated by the accompanying Graphs Nos. I to IV. All results are calculated on 1 kilogramme of starting material. Example A employs as a catalyst copper on pumice, Examples B, B¹, C and D have copper-iron catalysts.

EXAMPLE FOR IMPROVING THE OCTANE RATING OF N-HEPTANE

1 kg. n-heptane (B. P. 98-100°) was passed over the catalyst described in Example 1 at a

temperature of 580° C. and at a rate of 200 g. per hour. The reaction product consisted of 732 g. liquid and 250 litres=225 g. gas. The product was not completely aromatised, although a fraction of essentially pure benzene and toluene could be isolated, on fractionation. The incomplete aromatisation was indicated by the observation that only 15% of the liquid were soluble in dimethyl sulphate, which does not dissolve n-heptane at all. It was further observed that the liquid reaction product had a bromine consumption of 227 mg. grams while the initial n-heptane was entirely saturated. The initial n-heptane is converted by the process described, into a liquid which has the octane number 62.

The boiling range of the liquid as approximately shown in Graph V was as follows:

	°C.....	40
Up to 80°.....	per cent.....	3.0
80-85°.....	do.....	8.7
85-90°.....	do.....	14.7
90-95°.....	do.....	33.1
95-100°.....	do.....	28.2
Over 100° (mainly toluene).....	do.....	6.0

The following table summarises the results of the analysis of the scrubbed gas from this example, which gas had a specific gravity of 1.1403 g./litre (at 0° C. and 700 mm. pressure).

	Percent by volume	Percent by weight

GENERAL

In this connection it may be mentioned that the low-boiling aromatic hydrocarbons as such or their mixtures are useful as constituents of high-grade fuels for internal combustion engines, and also the mixture of higher alkylbenzenes (boiling range 140-180° C.), referred to above as one product of the process can be conveniently utilised for blending purposes, as its blending value has been determined to be 119.

The method gives a possibility to convert low-boiling (100-250° C.) gasolines into aromatics, either into single, well-defined hydrocarbons or into a mixture of aromatic compounds with unchanged or not wholly aromatised (cycloparaffinic, olefinic) hydrocarbons.

Variation of the conditions of reforming, both as to temperature and speed, permits to vary the ratio in which the single constituents of the aromatised products are formed—at least in certain limits.

This ratio also depends on the constitution and the molecular size (boiling range) of the charging stock, which may be selected from specific crudes, of paraffinic, naphthenic, aromatic or mixed bases, or their solvent extracts or raffinates or mixtures. Other suitable charging stocks are thermally or catalytically cracked gasolines, reformed gasolines or gasolines produced by polymerisation of C₃ and C₄ gases, e. g. deriving from this reforming process itself or else from any other source, or their solvent extracts or raffinates or mixtures.

Other suitable starting materials are the oils of convenient boiling range originating from the hydrogenation of coal or of high boiling mineral oils or of tars or of creosotes and similar materials or originating from synthetic processes such as the Fischer-Tropsch process.

In particular, it is possible to use as charging stock directly the products of thermal or catalytic cracking of higher boiling petroleum cuts, without previous condensation or any additional treatment. In this case the utilisation of those parts of the reaction products, which are gaseous at ordinary temperature and atmospheric pressure, is preferably carried out by using jointly the gases formed in the cracking and the reforming process, respectively. One can vary the nature of the aromatics formed, at least to a certain extent: higher temperature, e. g., gives more benzene at the expense of ethylbenzene.

The compositions of fractionated products given above may have a tolerance $\pm 2\%$.

The following is a list summarising suitable starting materials for the process according to the present invention, namely:

- (1) Natural materials: Paraffinic, naphthenic, aromatic or mixed crudes, their solvent extracts or raffinates.
- (2) Semi-synthetic materials:
  - (a) Products of a cracking or reforming process, carried out by thermal or catalytic methods with the crudes mentioned under (1), their mixtures, solvent extracts, or raffinates.
  - (b) Gasolines obtained by polymerisation processes from cracking gases, especially those with 3 and/or 4 carbon atoms, their mixtures, solvent extracts or raffinates.
  - (c) Products obtained by hydrogenation of coal, high-boiling mineral oils, tars, creosotes and other carbonaceous materials, the hydrogenation being carried out with or without catalyst, in one or more stages.

(3) Synthetic materials: Gasolines, obtained by synthesis from non-hydrocarbon materials, especially those originating from the catalytic reaction between carbon monoxide and hydrogen (Fischer-Tropsch process).

In connection with gasolines, those most appropriate for treating according to the present invention lie within the range 100 to 250° C. The invention is applicable to gasolines of lower boiling range, but these already have considerable use, namely, as aviation spirit.

I claim:

15. In the manufacture of aromatic hydrocarbons from charging stocks of aliphatic and hydroaromatic mineral oils, the process which comprises passing such a charging stock in contact with a mixture of copper and iron at a temperature within the range of 600° to 750° C., at substantially atmospheric pressure and at a space velocity ranging from about 0.16 to 0.19 liter per liter of catalyst per hour, whereby a reaction product is obtained the liquid portion of which consists substantially completely of aromatic hydrocarbons aside from a small low-boiling, highly unsaturated fraction, and recovering said aromatic hydrocarbons.
20. In the manufacture of aromatic hydrocarbons from natural gasolines having boiling points within the range of about 100° to 250° C., the process which comprises passing such a gasoline in vapor form in contact with a finely-divided metal catalyst capable of catalyzing hydrogenation and dehydrogenation reactions, at a temperature within the range of about 600° to 750° C., at substantially atmospheric pressure and at a space velocity ranging from about 0.16 to 0.19 liter per liter of catalyst per hour, and condensing the resulting vapors, whereby a liquid reaction product is obtained which, aside from a small, low-boiling, highly-unsaturated fraction, consists substantially of aromatics covering the entire range from benzene to polycyclic compounds.
25. In the manufacture of aromatic hydrocarbons from natural gasolines having boiling points within the range of about 100° to 250° C., the process which comprises passing such a gasoline in vapor form in contact with a finely-divided metal catalyst capable of catalyzing hydrogenation and dehydrogenation reactions, at a temperature within the range of about 600° to 750° C., at substantially atmospheric pressure and at a space velocity ranging from about 0.16 to 0.19 liter per liter of catalyst per hour, and condensing the resulting vapors, whereby a liquid reaction product is obtained which, aside from a small, low-boiling, highly-unsaturated fraction, consists substantially of aromatics covering the entire range from benzene to polycyclic compounds.
30. In the manufacture of aromatic hydrocarbons from natural gasolines having boiling points within the range of about 100° to 250° C., the process which comprises passing such a gasoline in vapor form in contact with a finely-divided metal catalyst capable of catalyzing hydrogenation and dehydrogenation reactions, at a temperature within the range of about 600° to 750° C., at substantially atmospheric pressure and at a space velocity ranging from about 0.16 to 0.19 liter per liter of catalyst per hour, and condensing the resulting vapors, whereby a liquid reaction product is obtained which, aside from a small, low-boiling, highly-unsaturated fraction, consists substantially of aromatics covering the entire range from benzene to polycyclic compounds.
35. In the manufacture of aromatic hydrocarbons from natural gasolines having boiling points within the range of about 100° to 250° C., the process which comprises passing such a gasoline in vapor form in contact with a finely-divided metal catalyst capable of catalyzing hydrogenation and dehydrogenation reactions, at a temperature within the range of about 600° to 750° C., at substantially atmospheric pressure and at a space velocity ranging from about 0.16 to 0.19 liter per liter of catalyst per hour, and condensing the resulting vapors, whereby a liquid reaction product is obtained which, aside from a small, low-boiling, highly-unsaturated fraction, consists substantially of aromatics covering the entire range from benzene to polycyclic compounds.
40. In the manufacture of aromatic hydrocarbons from natural gasolines having boiling points within the range of about 100° to 250° C., the process which comprises passing such a gasoline in vapor form in contact with a finely-divided metal catalyst capable of catalyzing hydrogenation and dehydrogenation reactions, at a temperature within the range of about 600° to 750° C., at substantially atmospheric pressure and at a space velocity ranging from about 0.16 to 0.19 liter per liter of catalyst per hour, and condensing the resulting vapors, whereby a liquid reaction product is obtained which, aside from a small, low-boiling, highly-unsaturated fraction, consists substantially of aromatics covering the entire range from benzene to polycyclic compounds.
45. In the manufacture of aromatic hydrocarbons from natural gasolines having boiling points within the range of about 100° to 250° C., the process which comprises passing such a gasoline in vapor form in contact with a finely-divided metal catalyst capable of catalyzing hydrogenation and dehydrogenation reactions, at a temperature within the range of about 600° to 750° C., at substantially atmospheric pressure and at a space velocity ranging from about 0.16 to 0.19 liter per liter of catalyst per hour, and condensing the resulting vapors, whereby a liquid reaction product is obtained which, aside from a small, low-boiling, highly-unsaturated fraction, consists substantially of aromatics covering the entire range from benzene to polycyclic compounds.

CHARLES WEIZMANN.
